UNITED STATES PATENT OFFICE.

JAMES FORD BELL, OF MINNEAPOLIS, MINNESOTA.

ART OF PRINTING.

No. 819,841.

Specification of Letters Patent.

Patented May 8, 1906.

Application filed December 9, 1905. Serial No. 291,080.

To all whom it may concern:

Be it known that I, JAMES FORD BELL, a citizen of the United States, residing at Minneapolis, county of Hennepin, and State of Minnesota, have invented certain new and useful Improvements in the Art of Printing, of which the following is a specification.

My invention relates to the art of printing, and particularly to the production of pictures in more than one color.

The object of the invention is the improvement of the method of producing prints or pictures having opaque and transparent portions of different colors.

In carrying out my method or process I use as a printing-surface partially-transparent paper or other suitable material, preferably white, and print on its face in the ordinary way the portions of the picture that are intended to be visible when viewed by reflected light. The corresponding portions of the back of the sheet may either be printed at the same time or afterward stenciled with an opaque ink or paint to prevent the transmission of light through the portions of the sheet thus printed. I then stencil or print with translucent color or colors the uncolored spaces on the back of the sheet. The picture produced by this method when viewed by reflected light will show only its face print and colors, with intervening spaces of the original color of the paper; but when viewed by light transmitted through it will show also the colors that have been applied on the back of such spaces.

In the accompanying drawing is shown a

sectional view of a picture printed on paper in accordance with my process, the paper and print being shown in exaggerated thickness.

In such drawing the reference-figure 1 designates a sheet of partially-transparent paper; 2, the print of the picture on the front of the paper; 3, the opaque print on the back of the paper, and 4 the print with translucent color in the spaces intervening the 40 opaque print on the back of the paper. Thus, for illustration, the picture may be that of a building which when looked at in reflected light will show the building with white windows, but when viewed by light 45 transmitted through the window portions will show the translucent colors with which their backs are coated.

What I claim as my invention, and desire to secure by Letters Patent, is—

The method of printing, which consists in printing on portions only of the face of partially-transparent material; printing or stenciling corresponding portions of the back of the material to render them opaque; and 50 lastly printing or stenciling with translucent color or colors the blank spaces intervening the opaque portions on the back of the material.

In testimony whereof I have signed my 55 name to this specification, in the presence of two subscribing witnesses, this 29th day of November, 1905.

JAMES FORD BELL.
